(57) **CLAIM**

(22) Filed: **Jan. 5, 2005**

The ornamental design for a removable head for a fishing
lure, as shown and described.

(51) LOC (8) Cl. **22-05**

DESCRIPTION

(52) U.S. Cl. **D22/133**

FIG. 1 is a perspective view of a removable head for a
fishing lure according to the invention affixed to a fishing
lure.

(58) **Field of Classification Search** D22/125-133;
43/42.06, 42.35, 42.36, 42.05, 42.17, 42.16,

43/42.09, 42.28, 42.48, 42.45, 42.44, 42.11

See application file for complete search history.

FIG. 2 is a top view of the removable head of FIG. 1.

(56) **References Cited**

FIG. 3 is a bottom view of the removable head of FIG. 1.

U.S. PATENT DOCUMENTS

FIG. 4 is a left side view of the removable head of FIG. 1.

5,522,170 A * 6/1996 Cole 43/42.11
D372,955 S * 8/1996 Gill et al. D22/128
D375,343 S * 11/1996 Jones D22/128
D431,626 S * 10/2000 Troyer D22/133
D495,024 S * 8/2004 Roberts D22/133

The right side view of the removable head is a mirror image
of the left side view of the removable head.

FIG. 5 is a front view of the removable head of FIG. 1; and,

FIG. 6 is a rear view of the removable head of FIG. 1.

The broken line showing of environment in the drawings is
for illustrative purposes only and forms no part of the
claimed design.
